United States Patent Office.

JOEL GARFIELD, OF GROTON, MASSACHUSETTS.

Letters Patent No. 64,093, dated April 23, 1867.

IMPROVEMENT IN HAY AND COTTON PRESS.

The Schedule referred to in these Letters Patent and making part of the same.

TO ALL WHOM IT MAY CONCERN:

Be it known that I, JOEL GARFIELD, of Groton, in the county of Middlesex, and State of Massachusetts, have invented an improved Hay and Cotton Press; and I do hereby declare that the following, taken in connection with the drawings which accompany and form part of this specification, is a description of my invention sufficient to enable those skilled in the art to practise it.

My invention relates to that class of vertical box presses for compressing hay, cotton, &c., in which a follower is intermittently and progressively forced down by the action of toggle-levers, and suitable co-operative ratchet and pawl mechanism, and the invention consists primarily in the arrangement, upon each end of the press, of a pair of horizontal shafts or pins, whose opposite ends extend into and slide freely in vertical ways or grooves; said shafts extending through the two arms of a toggle-joint, and the two shafts carrying feeding and retaining pawls, working in the teeth of vertical ratchet plates, one of the shafts being hung from the follower, and the upper toggle-arm having a lever extending from it, by vibrating which the upper pawls are drawn down over the ratchet, while the lower ones are held stationary, and, alternately, the lower ones are slid down the ratchet, while the upper ones are held stationary, thus effecting a progressive downward movement of the follower.

The drawings represent a press embodying my invention, A showing an end view, and B a central longitudinal section of the same. C, a side view of the ratchet pawls and their actuating lever.

a denotes the vertical box or frame, in which the hay is received and compressed. b, the follower, fitting and sliding freely within the same; said follower being suspended by cords or chains c, from a tilting frame, d, the cords running over guide-sheaves or pulleys e f, to a windlass, g. In the opposite ends of the box or frame a are vertical openings h, into which extend the opposite ends of the follower-beam i, and on the outer surface of each end wall, at the sides of this opening, are vertical ways or grooves k, in each pair of which run two horizontal shafts or pins l o, the lower one of which is hung in bearings in a link, m, depending from the beam i, while the upper one is connected to the lower pin, and is held in position in the grooves k, and with relation to such lower pin by a toggle-joint, n x, as seen in the drawings. Each pin carries a pair of pawls, p or q, which engage with vertical ratchets r, at the sides of the groove k, and the upper arm of each toggle-joint has an actuating lever s, extending outwardly, as shown at B and C.

When the press is to be charged with hay, the pawls are all disengaged from the ratchets, and the follower is drawn up to the top of the press by the windlass g, the links m are swung out from the beam i, and the follower is removed from the press, or is tipped up vertically at the top of the same. Sufficient hay being then introduced, the follower is returned, the links m are swung back over the ends of the follower-beam, the ratchet on the windlass is released from its retaining pawl, the pawls p q are carried back into engagement with their ratchets, and each lever s is thrown up into the position shown at C. By now carrying down each lever into horizontal position it will readily be seen that while each upper pin or shaft l is kept from moving by its pawls engaging with the teeth of the ratchets, the lower pins or shafts o are forced down by the straightening of the toggle-levers or arms, as shown at B, carrying with them the links m and follower b. If the lever is now swung back, the lower pawls become the retaining pawls, being held stationary by the ratchets, while the upper pawls slip down toward them, as seen at C. By again forcing down the levers, the lower pawls are again forced down, while the upper ones remain stationary, again forcing down the follower as before; this alternate downward movement and retention of the respective pawls being kept up until the hay is sufficiently compressed, the pawls being kept at all times in proper relative position with relation to the ratchet teeth, by the grooves k, and toggle-arms n x, while the intermittent progressive movement of the follower is being effected. The follower is hung to a swinging frame, d, which is hinged to the case a, in such a manner that it can be turned up on its hinges from its horizontal position to a vertical position, and when the follower is drawn to the top of the press and is released from the links m this frame is turned up into vertical position, carrying with it the follower, and thus leaving the press entirely open at top for introduction of the hay or other material to be pressed.

I claim, in combination with the follower, the grooves or ways at the ends of the press, and their sliding pins, the vertical ratchets and their double set or sets of pawls, and the toggle-levers, when so arranged that an intermittent progressive movement is imparted to the follower by their co-operative movements, substantially as set forth.

Also in combination with the follower, the hinged frame d, by which the follower may be swung up to leave the press open, substantially as set forth.
